(57) **CLAIM**

The ornamental design for a smart bidet as shown and described.

DESCRIPTION

FIG. 1 is a first perspective view of a smart bidet showing my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof; and,

FIG. 8 is a second perspective view thereof.

The broken lines in the drawings depict portions of the smart bidet that form no part of the claimed design.

1 Claim, 8 Drawing Sheets
